Frank J. Leek

UNITED STATES PATENT OFFICE

LYMAN MIDDLEDITCH, OF NEW YORK, N. Y., ASSIGNOR TO L. MIDDLEDITCH COMPANY,
OF NEW YORK, N. Y., A CORPORATION OF NEW YORK

LOOSE LEAF ASSEMBLY

Application filed June 20, 1929. Serial No. 372,248.

This invention relates generally to loose leaf assemblies such as memorandum pads, bridge-score cards and so forth.

One type of loose leaf assemblies consists essentially of a backing member having posts and a pack of sheets resting on the backing member and engaging the posts, the sheets being removable one by one without leaving a pack of stubs adjacent the posts. It will be appreciated that, when a fresh pack of sheets is placed in position on the posts and backing member, said posts project but slightly above the pack of sheets, but that, as the sheets are removed one by one, said posts will become more and more exposed thereby destroying the symmetry of the device and presenting an unsightly appearance.

The main object and feature of this invention is the overcoming of the above objection.

In the accompanying drawing the invention is disclosed in several concrete and preferred forms in which:

Fig. 1 is a top plan view of a device embodying the invention;

Fig. 2 is a vertical sectional view substantially on the plane of line 2—2 of Fig. 1;

Fig. 3 is a vertical sectional view approximately at right angles to that of Fig. 2 and substantially on the plane of line 3—3 of Fig. 1; and

Fig. 4 is a fragmentary detail sectional view showing a modification of the invention.

1 indicates a backing member of any suitable construction, 2 are upright posts and 3 denotes a pack of sheets supported by the backing member and engaging the posts. The sheets are provided with perforations 4 at the point where they engage the post so arranged that an entire sheet may be removed, that is to say: the sheet is not torn off so as to leave a stub. As the pack of sheets diminishes the posts will become more and more exposed and it is desirable to overcome this objectionable feature. The backing member is therefore so arranged that one end of it has a greater elevation than the other, and the posts are frictionally held at said end of greater elevation and have a telescoping

relation thereto. Various means may be employed for this purpose, but, in the present instance, they take the following form: Hollow legs 5 are associated with hollow clamping means. In Figs. 1 to 3 inclusive each of the hollow clamping means consists of a thimble 6, having a head 7, externally threaded but passing freely through the backing member, and a locking nut 8. In the form here shown the threaded thimble extends far enough down to receive internally threaded portion 9 of hollow leg 5. Each of posts 2 consists of a tubular member having a slit 10 to admit of slight expansion to frictionally hold it in the backing member or the devices carried thereby. It will now be understood that when a new pack of sheets is placed in position posts 2 will be in an upper position and that as the height of the pack of sheets diminishes the posts may be pressed downwardly so that they will not protrude unduly.

In Fig. 4 is shown a modification of the hollow clamping means, which here consists of a thimble 12 having near one end two spaced-apart flanges 13 and 14 between which the backing member is clamped. In this instance, hollow sheet metal leg 15 is frictionally carried on the thimble below the backing member and is therefore provided with a slit 16 similar to slit 10 in the upright posts.

The advantages of this invention are that the device always presents a neat appearance, that an inclined writing surface is obtained, that the unused portion of the posts is nested within supporting means, and finally that all adjustments are made with a minimum of effort.

11 is a loose weight which slides loosely on the posts to keep the sheets alined; and the particular loose leaf assembly here shown, except the telescoping feature, is fully set forth and explained in Patent No. 1,669,528 of May 15, 1928.

The present application is a continuation, in part, of one filed November 8, 1927, Ser. No. 231,845.

I claim:

1. The combination with a backing member for a loose-leaf assembly, of hollow clamp-

- ing means extending through the backing member and engaging opposite faces of said backing member, a hollow supporting leg carried by said clamping means below the backing member, and an upstanding post frictionally held within the clamping means and extending above the backing member.
2. The combination with a backing member for a loose-leaf assembly, of hollow clamping means consisting of a thimble extending through said backing member and having two spaced-apart flanges near one end between which the backing member is clamped, a hollow supporting leg carried at the other end of said thimble and below the backing member, and an upstanding post frictionally held within the thimble and extending above the backing member.
3. The combination with a backing member for a loose-leaf assembly, of hollow clamping means consisting of a thimble extending through said backing member and having two spaced-apart flanges near one end between which the backing member is clamped, a hollow supporting leg frictionally held at the other end of said thimble and below the backing member, and an upstanding post frictionally held within the thimble and extending above the backing member.
4. In a device of the character described, a base, a pad, a bushing extending through said base, retaining means for said pad received within said bushing, and a support for said base carried externally on said bushing.
5. In a device of the character described, a base, a pad positioned on said base, said pad having spaced apart perforations adjacent one end thereof, corresponding perforations in the base, flanged bushings supported on the base and passing through the perforations of the base, socketed retaining legs engaging the exterior surface of the bushings and adapted to support the pad in an inclined position, means passing through the perforations in the pad and engaging said bushings for the purpose of securing the pad in position on the support.
6. The combination with a backing member for a loose leaf assembly, of hollow clamping means consisting of a thimble extending through said backing member and having two spaced-apart flanges near one end between which the backing member is clamped, a hollow supporting leg carried at the other end of said thimble and below the backing member, and an upstanding post held within the thimble and extending above the backing member.
7. Signed at the borough of Manhattan, city, county, and State of New York, this 18th day of June, 1929.

LYMAN MIDDLEDITCH.
